INVENTORS.
William W. Nevins,
and Robert L. Walker,
BY Mr. H. Campfield,
ATTORNEY

UNITED STATES PATENT OFFICE.

WILLIAM W. NEVINS, OF COLLEGE PARK, AND ROBERT L. WALKER, OF ATLANTA, GEORGIA, ASSIGNORS TO A. E. HILL MANUFACTURING COMPANY, OF ATLANTA, GEORGIA.

ELECTROSTATIC CONDENSER.

Application filed October 7, 1924. Serial No. 742,126.

To all whom it may concern:

Be it known that we, WILLIAM W. NEVINS and ROBERT L. WALKER, citizens of the United States, and residents of College Park, county of Fulton, and State of Georgia, and of Atlanta, county of Fulton, and State of Georgia, respectively, have invented certain new and useful Improvements in Electrostatic Condensers, of which the following is a specification.

This invention relates to an improved condenser of the fixed capacity type which has for its object, first, to provide one that is enabled to maintain a more constant capacity due to the fact that the assembling of its elements is accomplished to keep these elements under proper pressure throughout the entire surface, and, consequently, there is no change in the pressure in the structure, and second, that it is one that possesses great mechanical strength, is compact and is symmetrical.

The invention is illustrated in the accompanying drawing in which Figure 1 is a top view of the condenser made according to our invention. Figure 2 is a side view and Figure 3 an end view of the device shown in Figure 1. Figure 4 is an enlarged cross section of the condenser before the top edge of the shell or casing is rolled over. Figure 5 is a similar view after the top edge has been so rolled. Figure 6 is a section on line 6—6 in Figure 7 and Figure 7 is a face view of one of the plates provided with an extension to act as a terminal.

The casing of the device is cup-shape, that is, it is cylindrical with an open top and is provided with the side walls 10 and the bottom 11, the side walls having gaps 12 which are suitably disposed usually on opposite sides of the casing. This shell is made of metal and acts as a container for the plates that go to make up the condenser.

To provide metal that is easily worked, the casing 10 is usually made of thin material and while the bottom portion can be made of greater thickness, it is usually more convenient to insert a bottom plate 13 of metal which is placed in the bottom of the shell and is of substantially the same diameter as the inside of the shell and thus insures proper thickness to provide sufficient mechanical strength.

On top of this we place alternate sheets of dielectric material 14 and sheets of active material 15, the dielectric material being of a diameter to fit just inside the shell and the active material having a diameter somewhat less so that there is no contact of the side edges of the active material with the shell. 55

The lowermost of the plates 14 can be made of insulating material instead of dielectric material and so also with the top plate on which the metal plate 16, similar to the plate 13, is placed. These assembled parts are then subjected to pressure by suitable tools but preferably by a die so that the top edge 17 of the shell is rolled over as shown at 18 in Figure 5. This rolling is accomplished under sufficient pressure to cause 70 the assembled plates to be firmly pressed together over their entire surface, the plates 13 and 16 being of sufficient rigidity to insure this and there can be no displacing of the plates, this being an assurance of no variation in capacity. 75

The cylindrical or round type of construction permits of this even distribution of pressure which is not so feasible with small condensers having a square or rectangular form. Such of the plates 15 of active material as are to be used as terminals are provided with lips 19 which project out through the gap 12 and are fastened by the eyelets 20 which at the same time are used for fastening the soldering tip 21 thereto. This construction insures the mechanical and electrical connection between the proper plates to form the terminals. 80

The device is symmetrical in appearance, 90 is of great mechanical strength, and the edges 17 are assured of a complete rolling over or contact with the assembled plates in the condenser by reason of the distortion of metal possible by reason of the gaps in the 95 side walls of the shell.

While the cylindrical form is preferred, it will be evident that a cup-like casing or various other forms such as three-cornered or oblong shapes can also be manufactured embodying this present construction. 100

We claim:

1. A condenser comprising a cylindrical shell with an open end and gaps in its side walls, metal plates and plates of dielectric material alternately placed in said shell, the 105

shell having rolled edges to cause said edges to press on the plates in the shell to keep the plates under an even distribution of pressure to maintain a constant capacity.

- 5 2. A condenser comprising a cup-shaped shell, with opposed gaps in its sides, a series of plates in the shell, selected plates having lips projecting through the gaps to provide

terminals, the shell having its top edge rolled over to bear with pressure on the contents 10 of the shell.

In testimony that we claim the foregoing, we have hereto set our hands, this 4th day of Oct., 1924.

WILLIAM W. NEVINS.
ROBERT L. WALKER.
